UNITED STATES PATENT OFFICE.

EDUARD SCHMITT, OF CHEMNITZ, GERMANY, ASSIGNOR TO C. G. HAUBOLD, A. G., OF CHEMNITZ, GERMANY, A CORPORATION OF GERMANY.

ROLLER AND DRUM.

Application filed November 25, 1924, Serial No. 752,098, and in Germany June 1, 1923.

My invention relates to improvements in rollers and drums such as are used in machines for bleaching, dyeing, and wet dressing of textile matter. Rollers and drums of this kind must be proof against the action of lyes, acid, chlorine, and other chemicals, for which reason they are provided with coatings of copper, brass, bronze, and the like, or they are made from such metals. 5 Rollers or drums which have thus been coated are expensive, and where they are comparatively long they can not be made with small diameters, as is frequently desired. In hollow rollers the coatings have been dispensed with by constructing the same with strong walls and from vulcanized rubber or tempered steel. Rollers of this type show sufficient hardness, but they are very expensive, and when made from steel they 10 are to some extent subject to corrosion.

The object of the improvements is to provide rollers or drums for machines of the class referred to which are durable, and proof against corrosion and which can be manufactured at low cost, and with this object in view I construct the said rollers or drums from iron or sheet iron having a chromized surface. Thereby I am enabled to construct the body of the roller or drum 15 from low grade iron, and more particularly I am enabled to construct the drums from sheet metal.

For the purpose of explaining the invention several examples embodying the same have been shown in the accompanying drawing in which the same reference characters have been used in all the views to indicate corresponding parts. In said drawing,

Fig. 1, is a sectional view showing a tubular roller,

Fig. 2, is an elevation showing a solid roller,

Fig. 3, is a sectional view showing a feeding or guiding drum.

Fig. 1 shows a tubular roller made from a seamless iron pipe *e* mounted on a shaft *a* through the intermediary of hubs *d*. In one construction the dimensions are: length of the pipe 2250 millimeters, diameter 90 millimeters. The chromized skin *ch* of the roller has been indicated in dotted lines. The rollers shown in the figure are designed for use in wet dressing in mercerizing machines, cylinder drying machines, dressing

machines, and steam machines, and for dry 55 dressing in gas singes, oxidation machines and drying machines for the delivery of the goods.

Fig. 2 shows a solid roller *v* made from low grade iron and provided with a chromized skin *ch*. In one construction the dimensions are as follows: length of the roller excluding the trunnions 4000 millimeters, diameter 700 millimeters. A roller of this type is used for squeezing purposes, but it 60 may also be used for calendering paper and the like.

Instead of solid rollers I use in many cases tubular rollers having thick walls and provided with heating means. By providing the rollers with chromized skins I may manufacture the same from a low grade iron which by reason of the chromized surface has high corrosion resisting properties and takes a high polish. Such rollers 70 which are made with thick walls and median diameters are used as pressing rollers for wet dressing in broad washing and acid machines, squeezing machines, dyeing machines of any type, wet calenders and dry 75 dressing in calenders.

Fig. 3 shows a drum made from a sheet iron cylinder *b* mounted on end disks *s₁* and *s₂* and coated with chromium, as is shown at *ch*. Drums of this type are used as guiding means in wet and dry dressing machines, paper making machines, and the like.

The surface of the rollers or drums may be chromized by any known or preferred 90 process, for example by the process which consists in heating the metal under non-oxidizing conditions in contact with a powdered charge containing metallic chromium at a temperature below the melting point of 95 either metal.

I claim:

A rotating iron body adapted to produce pressure, particularly for use in machines for bleaching, dyeing and the wet dressing 100 of textile materials, having a chromized surface, whereby said surface is rendered not only rust and acid resistant but also very hard.

In testimony whereof I hereunto affix my signature.

EDUARD SCHMITT.
